Primary Examiner — Christy Nemeth

(57) **CLAIM**

The ornamental design for an electric toothbrush charger, as shown and described.

DESCRIPTION

FIG. 1 is a top perspective view of an electric toothbrush charger of my new design, according to a first embodiment; FIG. 2 is a bottom perspective view thereof; FIG. 3 is a front view thereof; FIG. 4 is a rear view thereof; FIG. 5 is a left side view thereof; FIG. 6 is a right side view thereof; FIG. 7 is a top view thereof; FIG. 8 is a bottom view thereof; FIG. 9 is a top perspective view of an electric toothbrush charger of my new design, according to a second embodiment; FIG. 10 is a bottom perspective view thereof; FIG. 11 is a front view thereof; FIG. 12 is a rear view thereof; FIG. 13 is a left side view thereof; FIG. 14 is a right side view thereof; FIG. 15 is a top view thereof; FIG. 16 is a bottom view thereof; and, FIG. 17 is an enlarged detail view of area 17 in FIG. 2. The dot-dash broken lines in the drawings are for the purpose of indicating the portions shown enlarged in the drawing views and form no part of the claimed design.

1 Claim, 17 Drawing Sheets
